UNITED STATES PATENT OFFICE

2,612,416

RAILWAY JOURNAL LUBRICATOR
DISTRIBUTOR

James J. Hennessy, Chambersburg, Pa., assignor
to Hennessy Lubricator Company, Inc., Cham-
bersburg, Pa., a corporation of Delaware

Application August 3, 1949, Serial No. 108,325

6 Claims. (Cl. 308—84)

1

The invention relates to the lubrication of railway axle journals and more particularly to a mechanical device mounted in an A. A. R. (American Association of Railroads) type journal box for pumping oil from the lower portion of the box to the journal on which the box is mounted.

Such devices usually include a pump proper and a distributor mounted thereon and applying oil from the pump to the axle journal. In such devices one of the difficulties is the insertion and removal of the pump and distributor through the outer open end of the journal box when the box, with the journal bearing and wedge, is mounted on the journal.

The general object of the present invention is to provide a distributor which can be inserted through the open end of the box and beneath the journal and after such insertion may be assembled readily with a mechanical pump unit also inserted through the open end of the box and beneath the journal.

It is necessary that the distributor be held in close contact with the journal during operation of the lubricator and throughout the life of the distributor and it is a further object of the invention to provide a distributor which will meet this condition.

The invention comprises a distributor member of substantial area composed of fibrous material, the member as a whole being bendable so that it may be readily inserted into and removed from the space between a journal and the bottom of a box mounted thereon. Preferably the distributor is supported from the bottom of the box in which it is inserted by an elongated spring leaf readily distortable with the distributor fibrous member to accommodate insertion and removal from the box. The distributor also includes a depending conduit through which lubricant may be supplied to the surface of the distributor, the conduit and associated parts being arranged to hold its lower end above the bottom of the journal box to facilitate application and removal of a pump.

In the accompanying drawings illustrating selected embodiments of the invention,

Figure 1 is a vertical longitudinal section through the lower portion of an A. A. R. journal box with one form of the novel distributor in functioning position, the associated pump assembled therewith.

Figure 2 is a detailed section corresponding to a portion of Figure 1 but drawn to a larger scale and showing the inner end of the pump withdrawn from beneath the central portion of the distributor.

2

Figure 3 is a transverse vertical section taken on the line 3—3 of Figure 2, but with the pump removed.

Figures 4 and 5 are diagrammatic views taken longitudinally and transversely of the distributor and showing how it may be fixed during insertion into and removal from the box.

Figures 6, 7, and 8 correspond to Figures 1, 2, and 3 but illustrate another form of the invention.

In the structure shown in Figures 1—5 the journal box 1 receives the journal 2 in the usual manner. A horizontally disposed holding plate P extends across the bottom of the box and is welded thereto at W. A pump 3 of the general type shown in my earlier Patent 2,331,835, issued October 12, 1943 is seated upon the bottom wall 4 of the box and is received in a longitudinal slot in plate P.

20 A distributor 5 is applied to the lower face of the journal and is thrust against the journal by flat springs 6 seated upon plate P. The body of the distributor comprises a plurality of pads 10 of felt or other suitable oil transmitting material having their upper edges cut arcuately to fit the journal surface. The lower corners of the pads are notched (Figure 3) to receive bendable sheet metal strips 11 which are mounted on springs 6 and extend from front to rear of the distributor near each side thereof. The ends of strips 11 are flanged upwardly at 12 and 13 to engage the outer faces of the end pads 10.

25 A rod 14 is associated with each strip 11 and extends through relatively large apertures therefore in all of the pads 10 and each rod has a head 14a at one end engaging the upturned flange 12 of the associated strip 11 and has a head 15 at the other end engaging the outer end of a coiled spring 16 which thrusts inwardly 30 against the bottom of a cup 17 having a flanged outer rim 18 seated on the adjacent flange 13 of strip 11.

35 The pads 10 are split vertically down the center of the distributor and these split sections are pulled together by transverse rods 19, springs 20, and spring cups 21, corresponding to the longitudinally disposed rods and cups and seated against depending legs 33 of angular clips having their horizontal legs secured between springs 50 6 and strips 11.

The pads at the center of the distributor body are apertured to receive a metal sleeve 22 which has a flanged top rim 23 and a wider flanged bottom rim 24. A tube 25 of leather or other flexible material is attached at its upper end to flange 24 and at its lower end to the flanged rim 26 of a

terminal 27 having a semi-spherical lower end. A helical spring 28 is seated against the bottom face of sleeve 22 and the upper face of terminal 27. A ball 29 and a port 30 in terminal 27 form a check valve.

The upper flange 23 of sleeve 22 is shaped to fit against the face of the journal and is received in suitable notches provided therefor in the adjacent felt pads 10. Oil is pumped through port 30, tube 25, and sleeve 22 to the journal and spreads over the latter. After initial saturation of the felt strips the journal is always lubricated, even at the beginning of a truck movement and before the pump may have supplied a substantial quantity of oil to the journal.

After the box and journal are assembled, the distributor is inserted between the holding plate and the journal and the lower face of terminal flange 26 slides over the edges of the longitudinal slot in holding plate P with the end of the terminal well above the box bottom wall 4, as shown in Figure 2, but lower than as shown in Figure 1. When the pump is inserted, its beveled inner end 34 is shoved beneath terminal 27 and raises the latter to the position shown in Figure 1. Inward movement of the distributor and pump is limited by the engagement of the top of terminal 27 with the inner end of the slot in plate P.

When inserting the distributor into the box beneath the journal and when removing the distributor from the box the sides of the body may be grasped by the hands and readily distorted as indicated in Figures 4 and 5 to facilitate the passage of the distributor through the restricted space between the end of the journal and the end of the box or strips 11 may bend to the extent necessary. At the same time, the long flat springs 6 are readily compressed by the operator, if necessary, to effect the passage of the distributor pad and springs between the journal and the box bottom.

The general arrangement shown in Figures 6, 7, and 8 corresponds to that shown in Figures 1, 2, and 3, but the arcuate distributor pad 40 consists of a single sheet of felt or other fabric material and is not divided lengthwise or transversely. It is relatively thinner than the felt strip previously described and a flexible sheet 41 of leather, metal, or plastic underlies the pad and is thrust against the journal by flat elliptic springs 42 disposed angularly with their lower portions engaging the box lower wall 4a and holding plate P'. A terminal 44 similar to conduit terminal 27 has an upwardly extending central sleeve 45 inserted within a flexible tube 46 which leads to an upper metal sleeve 47 received in an opening in pad 40, but only projecting part way through this pad. A collar 48, slideable on sleeve 45, has a flange 48a underlying a lip 52a on an upstanding flange 52 on holding plate P' at the inner end of the longitudinal slot in the holding plate. A spring 49 is compressed between collar 48 and a flange 53 on terminal 44 and thrusts the terminal to socket 50 in the inner end 51 of the pump 3a.

When the pump is withdrawn, terminal 44 is lowered by spring 49 until flange 53 rests upon the edge portions of the slot in the holding plate P' and the terminal is positioned above the bottom of the box as shown in Figure 7.

When the pump is inserted, the terminal is raised, compressing spring 49 which firmly seats the terminal in the pump socket 50 as shown in Figure 6.

With this construction the long elliptic springs

and the thin pad and flexible backing plate permit the distributor to be bent transversely and longitudinally as it is inserted in the space between the box and the journal, or is removed therefrom.

5 When the distributor is inserted, its terminal is slid into the slot in the holding plate with flange 53 above the plate and thereafter it is easy to insert the pump beneath it.

The details of the distributor may be varied other than as shown without departing from the spirit of the invention and the exclusive use of those modifications of the invention coming within the scope of the claims is contemplated.

What is claimed is:

15 1. In a distributor for a railway journal axle box lubricator, a series of flat pads arranged upright and face to face with their upper edges shaped to engage the surface of a journal to be lubricated, means yieldingly holding said pads face to face but accommodating the tilting of the pads about their upper edges and relative to each other to accommodate the insertion and removal of the distributor as a unit between a journal and the bottom of a box mounted thereon, the 20 pads being divided lengthwise of the distributor into two portions tilttable relative to each other about a central axis extending longitudinally of the distributor, there being means yielding restraining the two portions against tilting.

2. In a distributor for a railway journal axle box lubricator, a series of flat pads arranged upright with their opposing faces in contact and with their upper edges shaped to engage the surface of a journal to be lubricated, said pads being provided with aligned apertures spaced from their upper edges, an elongated rod extending through said apertures, the ends of the rod being retained against the corresponding pads to hold all the pads in contact, the apertures being substantially larger in diameter than the rod to accommodate tilting of the pads about their upper edges relative to the rod and to each other so that the journal engaging surface of the pads may be curved lengthwise of the distributor to facilitate its insertion and removal as a unit between a journal and the body of a box mounted thereon.

3. In a lubricant distributor for a railway journal axle box lubricator, a member of substantial area of fibrous material for application to the journal to be lubricated, supporting springs spaced transversely of said member, a conduit depending from said member between said springs and constructed to be lengthened and shortened, 50 a ball-shaped terminal on the lower end of the conduit for seating on a lubricant pump, and a lateral projection on said conduit above said terminal for engaging a support independently of the ball terminal to support the conduit and terminal above the bottom of the journal box independently of said springs when the terminal is not seated on a pump.

4. In a railway journal box lubricator, a holding plate comprising spaced portions constructed to rest upon the bottom of a journal box and to receive a lubricant pump between them, a lubricant distributor including a structure of fibrous material shaped to engage the surface of a journal to be lubricated, a supporting spring depending from said structure, a conduit depending from said structure and including a section of flexible material which may be distorted to vary the length of the conduit, a lower terminal on said conduit arranged to contact a pump beneath the level of said plate portions, a spring

yieldingly holding said section extended and thrusting said terminal away from said structure, and a lateral projection on said terminal about its lower end extending over said holding plate spaced portions and arranged to engage the latter and support said terminal if there is no pump beneath the terminal.

5. In a railway journal box lubricator, a holding plate comprising spaced portions constructed to rest upon the bottom of a journal box and to receive a lubricant pump between them, a lubricant distributor including a structure of fibrous material shaped to engage the surface of a journal to be lubricated, a supporting spring depending from said structure, a conduit depending from said structure and including an upper section of flexible material which may be distorted to vary the length of the conduit, and a lower section of rigid material provided with a terminal arranged to contact a pump between said plate portions, a spring surrounding said lower section and compressed between said terminal and a seat on said lower section and yieldingly holding said lower section extended and thrusting said terminal away from said structure, and a lateral projection on said terminal extending over said holding plate spaced portions and arranged to engage the latter and support said terminal if there is no pump beneath the terminal.

6. In a distributor for a railway axle journal lubricator, a plurality of felt-like pads of substantial thickness disposed face to face and with

aligned upwardly facing cut edges for application to a journal, said pads being arranged in pairs end to end transversely of the distributor and each provided with an upright shoulder facing outwardly of the distributor, a retaining strip extending lengthwise of the distributor along the pad shoulders at each side of the distributor, and a yielding tension member extending transversely of the distributor and engaging said strips and drawing them towards each other but yielding to accommodate relative inclination of the pads of each pair vertically about an axis extending longitudinally of the distributor intermediate its sides.
